CLAIM

The ornamental design for a sole for footwear, as shown and described.

DESCRIPTION

FIG. 1 is a front perspective view of a sole for footwear showing my new design;

FIG. 2 is a left side view thereof;

FIG. 3 is a right side view thereof;

FIG. 4 is a front view thereof;

FIG. 5 is a back view thereof;

FIG. 6 is a top view thereof; and,

FIG. 7 is a bottom view thereof.

The broken line showing of the upper, zipper, grommets, and portions of the sole in the drawings shows unclaimed subject matter.
